DEPTH CHARGE PROJECTOR

Cecil P. Caulkins, New London, Conn.

Application November 26, 1941, Serial No. 420,471

5 Claims.

(CL. 89—1)

This invention relates to improvements in depth charge projectors, and its object is to provide an arrangement by means of which conventional depth charges or bombs may be projected from existing type of guns without the loss of the arbors to which heretofore the depth charge containers have been rigidly affixed. More specifically, my invention relates to the provision of means for checking or snubbing the motion of a propelled arbor and arresting it in position for further use.

I will describe the invention in the following specification and will point out its novel features in appended claims.

Referring to the drawings,

Fig. 1 is an end elevation partly in section of an arrangement which embodies my invention applied to a Y-gun of standard construction;

Fig. 2 is a side elevation of the arrangement shown in Fig. 1;

Fig. 3 is an end elevation and Fig. 4 a side elevation of another arrangement which also embodies this invention.

10 designates the casing of a Y gun which forms its explosion chamber. This casing is mounted on a pedestal 11. 12, 12 designate two barrels which are welded to the casing at 13. The projectile, as in former practice, comprises a hollow cylindrical shell or arbor 20 closed at its inner end, as at 21, and having a head at its outer end on which is supported a container for the charge or bomb. According to former practice, the container casing or bomb 22 is permanently affixed to the arbor and when gas is injected into the explosion chamber under high pressure, as by the firing of a cartridge, an arbor and a charge container are shot out of each barrel.

According to the present invention the head which supports the charge container 22 is constructed as a frame 23, the inner end of which is curved to fit the lower half of the container and with straight sides 24, 24 and its other end constructed to clear the container. One end of the head is closed by a plate 25. 26, 26 designate flanges which extend from the head near the sides thereof. When a container is placed in the head it rests on the frame 23 with one of its ends abutting the plate 25. Then a bar 27 is put across its other end to hold it in place.

30 designates a snubber on the closed end 21 of the arbor. As shown, this snubber comprises an eye-bolt 31 and a plurality of compressible collars 32 of suitable material, such as soft rubber. 33 is a chain interconnecting the eye-bolt

31 with another eye-bolt 34 in the base of the casing 10.

40 is a stationary frame comprising a pair of arms 41, 41 having surfaces 42 which are parallel with but spaced from the axis of one of the gun barrels 12. The inner edges 43, 43 of these arms are parallel with each other and the flanges 26 of the arbor head slide over them.

When the gun is fired, the arbor and its head 10 with the charge container will be expelled to the positions in which they are shown in broken lines at 20A, 22A and 23A in Fig. 1. There the movement of the arbor will be arrested by the chain 33 which will then be straightened out into the 15 position designated by the broken line 33A. The charge container, however, is free to continue the movement imparted to it by the gun and it will be catapulted out of the frame 23. The arbor will then drop back on the frame 40 until the eye-bolt 31 rests upon a bumper 44 on the frame where the arbor is in a convenient position for re-loading.

In the arrangement illustrated in Figs. 3 and 4, 50 is a recoil and checking cylinder, one end of 25 which is supported on a base 51 near the gun pedestal 11 by a pivotal connection 52. Within the cylinder 50 is a piston 53 which is connected by a rod 54 to an arm 55 which extends laterally from the frame 23 of the arbor head. These 30 parts are so proportioned and arranged as to position the rod 54 in substantial parallelism with the axis of the gun barrel. The cylinder 50 is slotted through the greater part of its length, as shown at 56, so that the piston 53 may move freely therein, but its outer end 57 is closed to form a dashpot.

When the gun with this arrangement is fired, the arbor and its head with the charge container will be expelled to the positions in which they are shown in broken lines at 20A, 22A and 23A in Fig. 3, in the manner described previously. In this case the movement of the arbor and its container supporting frame will be retarded and then brought to rest in a position 45 where they will be supported on the frame 40.

The embodiments of this invention which have been shown and described are designed for use with Y guns in which case, of course, arresting devices may be associated with each barrel. The 50 invention is not limited to this type of gun, and other structural modifications than those shown for illustrative purposes may be made without departing from its spirit and scope. I intend no limitations other than those imposed by the appended claims.

What I claim is:

1. A depth charge projector comprising an open muzzled gun barrel, a support therefor, an arbor having a diameter corresponding to the caliber of the gun barrel adapted to be inserted in the gun barrel, said arbor having an enlarged head on its outer end arranged to receive and support a depth charge, guides for said head outside of and parallel with the gun barrel combined with means for arresting the movement of the arbor connected with the head and with the support for the gun barrel.

2. A depth charge projector comprising an open muzzled gun barrel, a support therefor, an arbor having a diameter corresponding to the caliber of the gun barrel adapted to be inserted in the gun barrel, said arbor having an enlarged head on its outer end arranged to receive and support a depth charge combined with external means for arresting the movement of the arbor, said means comprising a cylinder parallel with the gun barrel, a piston in the cylinder, one end of said piston being connected to the support for the gun barrel, and means for interconnecting the piston and the enlarged head on the arbor.

3. A depth charge projector comprising an open muzzled gun barrel, a support therefor, an arbor having a diameter corresponding to the caliber of the gun barrel adapted to be inserted in the gun barrel, said arbor having an enlarged head on its outer end arranged to receive and support a depth charge combined with external means for arresting the movement of the arbor, said means comprising a cylinder parallel with the gun barrel, a piston in the cylinder, said cylinder being constructed with an opening through its wall throughout the greater part of its length and being closed at its outer end, the inner end of said piston being connected to the

support for the gun barrel, and a piston rod affixed to the piston extending through the closed end of the cylinder and affixed to the enlarged head on the arbor.

5. 4. A depth charge projector comprising an open muzzled gun barrel, a support therefor having a diameter corresponding to the caliber of the gun barrel adapted to be inserted in the gun barrel, said arbor having an enlarged head on its

10 outer end arranged to receive and support a depth charge, guides for said head outside of and parallel with the gun barrel combined with external means for arresting the arbor, said means comprising a cylinder parallel with the gun barrel, one end of said piston being connected with the support for the gun barrel, a piston within said cylinder, and means for interconnecting the piston and the enlarged head on the arbor.

15 20. 5. A depth charge projector comprising an open muzzled gun barrel, a support therefor, an arbor having a diameter corresponding to the caliber of the gun barrel adapted to be inserted in the gun barrel, said arbor having an en-

25 larged head on its outer end arranged to receive and support a depth charge, guides for said head outside of and parallel with the gun barrel combined with external means for arresting the arbor, said means comprising a cylinder parallel

30 with the gun barrel, said cylinder being constructed with an opening through its wall throughout the greater part of its length and being closed at its outer end, the inner end of said cylinder being connected to the support for the

35 gun barrel, a piston within the cylinder, and a piston rod affixed to the piston extending through the closed end of the cylinder and affixed to the enlarged head on the arbor.

CECIL P. CAULKINS.
